UNITED STATES PATENT OFFICE.

THOMAS DIXON SMYTHE, OF SANTIAGO, CHILE.

HEAVY FIELD ARTILLERY.

SPECIFICATION forming part of Letters Patent No. 737,972, dated September 1, 1903.

Application filed July 5, 1902. Serial No. 114,496. (No model.)

To all whom it may concern:

Be it known that I, THOMAS DIXON SMYTHE, a subject of the King of Great Britain, and a resident of Santiago, Chile, have invented new and useful Improvements in Heavy Field Artillery, of which the following is a full, clear, and exact description.

The object of the invention is to provide certain new and useful improvements in artillery whereby field-guns of great length, large caliber, and heavy weight can be readily transported from one place to another and brought quickly into action with great precision and steadiness and without unduly exposing the gun and the gunners to the fire of the enemy or rendering necessary a heavy shield.

The invention consists of certain parts and details and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a sectional side elevation of the improvement on the line 1-1 of Fig. 2, showing the gun-barrel mounted on the gun-barrel-transportation vehicle and ready to be lowered to the firing-carriage. Fig. 2 is a plan view of the same with the seat removed and the firing-carriage omitted. Fig. 3 is a rear end elevation of the improvement as shown in Fig. 1. Fig. 4 is a sectional side elevation of the improvement, showing the gun lowered upon the firing-carriage. Fig. 5 is a sectional side elevation of an improved form of suspension device for holding the gun-barrel in position on the crank-axle of the two-wheeled transportation-vehicle. Fig. 6 is an end elevation of the same. Fig. 7 is a plan view of the same. Fig. 8 is a longitudinal sectional side elevation of the firing-carriage suspended in its firing-carriage-transportation vehicle. Fig. 9 is a plan view of the same, and Fig. 10 is a rear end elevation of the same.

The gun-barrel A is adapted to be removably secured to the upwardly-extending crank-arm B' of an axle B, on which are mounted to rotate the usual wheels C of a two-wheeled ve-

hicle, of which the gun-barrel A is to form the pole. Now in order to removably secure the gun-barrel A to the crank B' at a point somewhat in the rear of the center of gravity I provide said gun-barrel A on the top with sets of lugs A', on which are secured the yokes D, by transversely-extending bolts E and E', as is plainly shown in Figs. 1 and 2, 60 said yokes D extending lengthwise and resting on top of the crank-arm B' of the crank-axle B. On the front of the axle B are formed lugs B', connected by braces F with pins A', formed on top of the gun-barrel A somewhat 65 in front of the lugs A', so as to hold the gun-barrel A against transverse shifting movement on the axle B.

Near the muzzle end of the gun-barrel A is formed a lug A', connected by a suitable hook G with the saddle cross-bar H, adapted to rest at its ends on the saddles H', carried by the horses, elephants, or other animals employed in drawing the gun and its suspended carriage over the field to its destination. The 75 animals are hitched to the doubletree, I fulcrumed on a pin A', projecting from the gun-barrel A in front of the pins A', and the said doubletree I is connected at its outer ends by rearwardly and inwardly extending braces I' 80 with a pin A', formed on the gun-barrel A, as is plainly shown in Fig. 1.

On the muzzle of the gun-barrel A is clamped a cap J, connected by the holding-back straps K with the harness of the team. 85 On the pins A' A' are secured the arms L' of the seat L for the teamster.

Now by the arrangement described the gun-barrel A when suspended on the transportation-vehicle can be readily moved from 90 one place to another, and when the gun arrives at its destination with the muzzle forward it is lowered into the cradle O of a firing-carriage P, set on the ground in the direction in which the firing is to be done by the 95 gun-barrel A. In order to lower the gun-barrel A into the cradle O, it is necessary to bring the several parts into the position shown in Fig. 1, and then the axle B' is locked to the wheels C by the use of pins N, engaging registering apertures in the flanges B', made integral with the axle B, and apertures in the hubs of the wheels C. (See Fig. 3.) When this has been done, the wheels C are turned to cause

the axle B to turn, so that the crank-arm B' of the axle swings forward and downward to lower the gun-barrel A and finally to deliver the same into the cradle O of the firing-carriage P. (See Fig. 4.) When the gun-barrel A is seated in position on the cradle O, then the operator removes the bolt E and swings the yokes or saddles D out of engagement with the crank-arm B' to dismount the axle from said yokes and allow of removing the wheels C and axles B B' from the gun-barrel A, so as to leave the latter unobstructed, it being understood that in the meantime the team has been unhitched and removed to allow the gunners to make use of the gun.

The firing-carriage P is provided with the usual recoil-cylinders Q, the pistons of which are adapted to be secured to the lugs A⁶ of the barrel, and with manipulating devices P' for the cradle O to point the gun-barrel in the desired direction—that is, the direction in which the shot is to be fired.

In order to transport the firing-carriage from one place to another, I employ a two-wheeled vehicle R (illustrated in Figs. 8, 9, and 10) and having the wheels R' journaled on the crank-axle R², supporting a frame R³, provided with a pole R⁴, and on said frame R³ are arranged a number of windlasses S, preferably actuated by the operator by means of ratchet wheels and levers, each windlass having its rope S' adapted to be secured to a lug on the base of the firing-carriage P, so that when the windlasses are actuated said firing-carriage is lifted into the position shown in Figs. 8, 9, and 10 and fixed by clamps to hold the bottom of the firing-carriage a suitable distance above the ground, it being understood that the crank in the axle R² permits of lifting the firing-carriage into said uppermost position. When the vehicle R has been run to its destination, the operator simply reverses the windlasses S to lower the firing-carriage P to the ground in position to receive the gun-barrel A, as above described.

I do not limit myself to the particular construction of suspension device for hanging the gun-barrel A on the crank B' of the axle B, as such suspension devices may be varied—for instance, as shown in Figs. 5, 6, and 7—the suspension device consisting, essentially, of an eyebolt T, engaged by a pin A⁷, held in the lugs A⁶, made integral with the barrel A, and on said bolt T screws a nut T', resting on top of the crank-arm B' of the axle B. The latter is connected by braces F with the gun-barrel, which is connected by braces I' with the doubletree, the same as above described.

In order to lower the gun-barrel A, it is simply necessary to unscrew the nut T' after previously locking the axle to the wheels by the pins N, which is done in this case to keep the crank in a vertical position while the gun-barrel is lowered onto its cradle, after which the pin A⁷ is removed.

From the foregoing it will be understood that apart from ammunition-wagons two separate wheeled vehicles are employed—one for transporting the gun-barrel and the other for carrying the firing-carriage to the place of action, the firing-carriage then being lowered onto the ground in the proper position to receive the gun-barrel in the manner described. Thus the ordnance will be ready for action in a very short time, and if it is desired to remount the gun-barrel and the firing-carriage it is only necessary to first reattach the gun-barrel to the axle B and turn the latter by the wheels C until the gun-barrel is out of the firing-carriage and the crank-arm is again in a vertical position and locked therein by the braces F, connecting the axle with the barrel. The carriage R is brought over the firing-carriage, so that the ropes can be attached, and then the firing-carriage is raised by windlasses S to its former position and clamped to the frame. It is further understood that during action the wheeled vehicles are removed to places of safety. By having the firing-carriage directly resting on the ground the gun-barrel is brought down as low as possible, thus preventing undue exposure of the gun and gunners to the fire of the enemy.

Having thus described my invention, I claim as new and desire to secure by Letters Patent—

1. The combination with a pair of wheels, and their axle, of a gun-barrel provided with pairs of lugs, and means connected with the lugs of opposite pairs and resting on the axle to hold the gun-barrel suspended therefrom, as set forth.

2. The combination with a gun-barrel, of a two-wheeled vehicle having a crank-axle, means for removably attaching the gun-barrel to the crank-arm of the axle somewhat to the rear of the center of gravity of the gun-barrel, and means for connecting the muzzle end of the gun-barrel with the team, as set forth.

3. The combination with a vehicle having a crank-axle, of means for suspending a gun-barrel from said axle, and a firing-carriage adapted to receive the gun-barrel on turning the crank-axle, as set forth.

4. A vehicle having a crank-axle for carrying a gun-barrel, wheels mounted to turn on said crank-axle, and means for locking the wheels to the axle to rotate the latter on turning the wheels, as set forth.

5. A vehicle having a crank-axle, wheels mounted to turn thereon, means for locking the axle to the wheels, and a suspending device for carrying the gun-barrel on the crank of the axle, to swing the gun downward and forward on turning the axle, as set forth.

6. A vehicle having a crank-axle, wheels mounted to turn thereon, means for locking the axle to the wheels, a suspending device for carrying the gun-barrel on the crank of

the axle, to swing the gun downward and forward on turning the axle, and a firing-carriage for receiving the gun, as set forth.

7. A vehicle having a crank-axle, wheels mounted to turn thereon, means for locking the axle to the wheels, a suspending device for carrying the gun-barrel on the crank of the axle, to swing the gun downward and forward on turning the axle, and a firing-carriage provided with a base and a cradle therein and adapted to receive the gun-barrel from said vehicle, as set forth.

8. The combination with a pair of wheels, and the axle, of a gun-barrel provided with lugs, means connected with the lugs and engaging the axle, whereby the barrel will be suspended from the axle, and a firing-carriage having a cradle constructed to receive and hold the gun-barrel so that the recoiling action of the gun-barrel will not be hindered by the lugs thereof, as set forth.

9. The combination of a gun-barrel, without a trail, which, during transit, is removably suspended at a point slightly to the rear of its center of gravity, in the raised crank of an axle on wheels; as also at another point near the muzzle from a cross-bar resting on the saddles of horses or other animals, the gun being at the same time used as a pole with its muzzle ahead and attached to the front harness of the team, and the crank-axle and cross-bar as set forth.

10. The combination with a crank-axle, and wheels thereon, of means for suspending a gun-barrel from the axle, and means for locking the axle to the wheels to permit the axle to be turned to lower the gun-barrel onto a firing-carriage, and to raise the same from the carriage into its suspended position when it serves as a pole, as set forth.

11. The combination with a crank-axle, and wheels thereon, of means for suspending a gun-barrel from the axle, means for locking the wheels to the axle, and means for detachably connecting the axle to the gun-barrel in front of the axle, as set forth.

12. The combination with a pair of wheels, and its axle, of means for suspending one end of a gun-barrel from the axle, and means whereby the other end may be supported from the backs of animals, as set forth.

13. The combination with a pair of wheels, and its axle, of means for suspending the breech end of a gun-barrel from the axle, means whereby the muzzle end of the barrel

may be supported from the backs of animals, and a device adapted to fit the muzzle of the barrel and provided with holdback-straps for connection with the harness of the team, as set forth.

14. The combination with a pair of wheels, and a crank-axle upon which the wheels are mounted, of means for suspending one end of a gun-barrel from the axle, a cross-bar adapted to be supported upon the backs of animals and to be connected with the muzzle end of the barrel, and a cap adapted to fit on the muzzle of the gun and provided with holdback-straps, as set forth.

15. The combination with a pair of wheels, and an axle, of a gun-barrel, means for suspending the gun-barrel from the axle, a doubletree fulcrumed on the gun-barrel, and rearwardly and inwardly extending braces secured to the doubletree and to the gun-barrel as set forth.

16. The combination with a pair of wheels, and a crank-axle, of a gun-barrel, means for suspending the gun-barrel from the crank-axle, and braces secured to the outer ends of the axle and extending forwardly and secured to the gun-barrel, as set forth.

17. The combination with a vehicle having a crank-axle, of a gun-barrel provided with pairs of lugs, and yokes connected with the said lugs and extending across the axle, as set forth.

18. The combination with a vehicle having a crank-axle, of a gun-barrel provided with pairs of lugs, yokes connected with said lugs and extending over the axle to suspend the gun-barrel from the axle, and a firing-carriage adapted to receive the gun-barrel when the axle is turned, as set forth.

19. The combination with a crank-axle, and wheels thereon, of a gun-barrel provided with lugs, yokes pivotally connected with the said lugs and extending over the axle to suspend the gun-barrel from the axle, and braces extending forwardly from the outer portions of the axle and having their forward ends detachably secured to the gun-barrel, as set forth.

In testimony whereof I have signed my name to this specification in the presence of two subscribing witnesses.

THOMAS DIXON SMYTHE.
